UNITED STATES PATENT OFFICE

100,785

DESIGN FOR A COMBINATION WASHING SINK, TUB, AND WRINGER

Constance W. Lance, Pittsburgh, Pa.

Application November 15, 1935, Serial No. 59,598

Term of patent 7 years

To all whom it may concern:

Be it known that I, Constance W. Lance, a citizen of the United States, residing at Pittsburgh, in the county of Allegheny and State of Pennsylvania, have invented a new, original, and ornamental Design for a Combination Washing Sink, Tub and Wringer, of which the following is a specification, reference being had to the accompanying drawing, forming part thereof.

The figure is a perspective view of a combi-

nation washing sink, tub and wringer, showing my new design.

The other side of the wringer is substantially the same in appearance as the front side shown. The back side of the tub portion of the design is flat and plain.

I claim:—

The ornamental design for a combination washing sink, tub, and wringer, as shown and described.

CONSTANCE W. LANCE.
